UNITED STATES PATENT OFFICE.

GEORGE N. BARTLETT, OF NATICK, MASSACHUSETTS, AND LEMUEL C. KINDALL, OF GROTON, NEW HAMPSHIRE.

NAILING-MACHINE.

SPECIFICATION forming part of Letters Patent No. 249,288, dated November 8, 1881.
Application filed October 3, 1881. (No model.)

To all whom it may concern:

Be it known that we, GEORGE N. BARTLETT, of Natick, county of Middlesex, State of Massachusetts, and LEMUEL C. KINDALL, of Groton, county of Grafton, State of New Hampshire, have invented an Improvement in Nailing-Machines of which the following description, in connection with the accompanying drawings, is a specification.

10 This invention in nailing-machines has especial reference to means for lifting headed nails or tacks from a hopper or receptacle and depositing the same in a guideway to pass to a driver.
15 In this our invention the nails are picked up singly by a fork mounted upon a lever, which, besides being moved in the arc of a circle, has a slight longitudinal movement at the proper time to discharge the nail from the fork of the lever into the guideway.

20 Figure 1 represents, in top view, a sufficient portion of a nailing-machine to illustrate our invention; and Fig. 2, a section thereof on the dotted line xx ; Fig. 1, the fall and dotted lines 25 of the lever showing the two positions of its fork with relation to the interior of the circular hopper containing the tacks or nails to be lifted.

25 The hopper a , to contain the tacks or nails b , is circular inside. The stud c has fixed to it the stationary cam d , which receives in its groove the stud or roller e or lever f , pivoted at g on the revolving disk or wheel h , secured to the rotating shaft i . The lever f , at its forward end, 30 is provided with a fork, l , adapted, as the lever is caused to sweep through the hopper a in the direction of the arrow in Fig. 2, to engage a tack or nail by its head, as shown by the dotted lever, and thereafter carry the said 35 tack or nail with it until the lever and fork reach nearly its full-line position, Fig. 2, when, by the shape of the cam d , the lever and fork are slightly withdrawn or moved back longitudinally to leave the head of the tack or nail 40 suspended between the upper end of the side rails of the guideway m , when it will slide down the said guideway, all as usual. Should 45 the head of the nail not be caught on the guide-

way, it will fall, as shown by nail b^2 , and, striking the lip n , will drop back into the hopper. 50 The inclination of the lever and fork when drawn suddenly back is sufficient to aid the tack in being discharged.

We have provided the interior of the hopper with a clearer, p , shown as a forked brush, 55 between which the fork, carrying one or more tacks or nails, passes as the fork of the lever f approaches the guideway, such clearer acting to brush off from the fork l such tacks or nails which may be lodged thereon crosswise. In 60 practice we shall employ a large number of these forked levers in one machine, a number of the said levers being carried by the same disk or wheel, and two or more such disks h may be employed.

65 The longitudinal motion imparted to the lever and fork is considered essential, for it frequently happens that the space at the upper end of the guideway is insufficient to receive the entire head of a nail, and should a part of the head of the nail be caught in the guideway, it is obvious that the fork l would be impeded in its movement unless drawn back beyond the said nail, but when drawn back a nail but partially lodged on the guideway may drop 70 back into the hopper.

75 We claim—

1. In a nailing-machine, the guideway and hopper to contain tacks or nails, combined with the forked lever mounted on the movable disk 80 or wheel, and with the cam to move the lever to withdraw the fork from below the head of the tack or nail, substantially as described.

2. The hopper and lever provided with fork l , to lift the nails therefrom, combined with the 85 brush to detach from the fork such nails as are improperly laid thereon, substantially as described.

In testimony whereof we have signed our names to this specification in the presence of 90 two subscribing witnesses.

GEORGE N. BARTLETT.
LEMUEL C. KINDALL.
